(57) **CLAIM**

The ornamental design for a United States Marine Corps combat utility uniform, as shown and described.

DESCRIPTION

FIG. 1 is a perspective view of a United States Marine Corps combat utility uniform, showing our new design.

FIG. 2 is a perspective view of an alternate embodiment of the United States Marine Corps combat utility uniform with the only differences residing in the hat.

FIG. 3 is a front view of the blouse;

FIG. 4 is a back view of the blouse;

FIG. 5 is a front view of the trousers; and,

FIG. 6 is a back view of the trousers.

The broken line showing of a person in FIGS. 1 & 2 is for illustrative purposes only and forms no part of the claimed design.
